DISPLAY APPARATUS

Clinton L. Walker, Piedmont, Calif.

Application November 20, 1935, Serial No. 50,799

4 Claims. (Cl. 248—123)

My invention relates to improvements in mobile display apparatus.

The broad object of my invention is to provide apparatus for use in service stations, by which merchandise can be displayed in position alongside of a vehicle being serviced, and capable of adjustment along the side of the vehicle so as to bring the displayed merchandise into reach of the occupants seated in the vehicle and permit them to help themselves to the articles so displayed.

Another object of my invention is to provide a display apparatus which can be moved into position after the vehicle has come to rest in the service station, and to mount it so that it will serve the two sides and ends of an "island".

Another object of my invention is to provide a display apparatus in which the display tray is arranged to be moved alongside of the vehicle, within reach of the occupants thereof, and which when out of use can be moved into an elevated position to prevent pilferage of the merchandise.

Another object of my invention is to provide a movable display device which can be fitted into a small space when out of use.

Another object of my invention is to provide a display device which is not cumbersome, nor difficult to move into position alongside the vehicle standing within its range.

Another object of my invention is to provide a pivoted, extensible display device in service stations, which device is so mounted as not to interfere with cars moving in and out of the station or with attendants in their work of servicing a vehicle.

Another object of my invention is to provide means in a pivotally mounted display device to prevent the marring or scratching of the vehicle.

Another object of my invention is to provide a self-balancing display tray, arranged to hold the tray in a generally horizontal position, regardless of the angle of inclination of the arm carrying the tray.

In the accompanying drawings, forming a part of this specification and in which like numerals are employed to designate like parts throughout the same;

Fig. 1 is a view in perspective, showing the display device mounted on a service station "island" and with the tray supporting arm extended full-length;

Fig. 2 is a view in perspective, showing the tray supporting arm fully telescoped and in its upward extending position of rest;

Fig. 3 is a side elevation view, partly in cross-section, showing the pivoting control means;

Fig. 4 is a view in perspective showing the end of the telescoping supporting arm in telescoped position and with the tray removed;

Fig. 5 is a detail in cross-section of the mounting for the display tray on the end of the telescoping arm;

Fig. 6 is a cross section detail view of the tray supporting arm telescoped and in the horizontal position;

Fig. 7 is a cross-section view of the telescoping arm in a partially extended position;

Fig. 8 is a cross-section on the line 8—8 of Fig. 3 but with a slightly modified form of base mounting; and

Fig. 9 shows a modified form of mounting the device.

It is the purpose of my invention to provide a display device for carrying merchandise direct to the side of a vehicle while it is in a service station. It is well known that the majority of customers who bring their vehicles to a service station for gasoline, oil, air, etc. remain seated in their machines and consequently do not have an opportunity to examine or inspect any merchandise which may be displayed in the service station or in non-mobile shelves or show-cases about the station. By means of my mobile display tray I provide the means for bringing this merchandise directly within reach of the motorist while seated in the vehicle. This permits him to inspect the merchandise and to help himself to whatever is on the display tray which he wishes to purchase.

With my device the station operator can place before the customer the merchandise on display and can then go about the task of servicing the car. During this interval the customer can make his selection of merchandise. Upon completion of the servicing operation the attendant can withdraw the tray, telescope the arm, and fold it up out of reach.

Broadly, my invention (see Fig. 1) is comprised of the mounting means A, the telescoping means B, the means C by which its position is regulated, and the pivotally mounted display means D.

The mounting means A, is usually made to be attached to the floor or to an "island" in a service station, although it is understood, as will subsequently be explained, that it may be attached to the roof, or to a vertical post, etc. An "island" is the term usually applied to a raised curbing which divides the traffic lanes in a service station, and on which the gasoline pumps, etc., are mounted.

In Fig. 1 I show my device mounted on such an island 20. The mounting means illustrated comprises the housing member 21, with a flange 22 at its base, serving to attach it to the island 20, and 5 with its top end closed at 23 to provide a walled recess or bearing 24. The other element of this mounting means comprises the tubular member 25, adapted to fit the bearing 24. At its upper end it is shaped to provide a boss 27 and a flat circular 10 anchor plate 28, having holes 30 and 31.

The telescoping means B, may be comprised of one or more tubular members adapted to slide one within the other, the number employed depending upon the maximum reach to be covered 15 and upon the length of each individual section which is practical and efficient. While I have illustrated these tubular members as square in cross-section, they may be round, oval, or any other shape.

20 In Figs. 1 and 2 I show the telescoping means B, made up of five short tubular sections 40, 41, 42, 43 and 44. Sections 41, 42 and 43 are substantially identical, except for size, and have the pivotally mounted rollers 45 sheathed in the 25 lower body extension 46; the stop lugs 47 which limit the extent which the sections can telescope; the spring mounted detents 48 on alternate sides and corresponding notches 50 in the wall of the adjacent inner section (see Fig. 7); and pivotally mounted rollers 51 concealed in the inner end of 30 each section. Except for size and, the location of the lugs 47 and detents 48, the intermediate telescoping sections, regardless of number employed, are identical.

35 It is desirable that there should be a minimum looseness or twist between the telescoping sections. I show one way of accomplishing this by having the upper inner surface of each member slotted longitudinally to provide a close-fitting 40 track for rollers 51. This slot 58 is shown in Figs. 3, 6 and 8. To prevent the sections from pulling apart when extended, I provide a stop plate 59 secured near the top inside end of each section.

45 The tip or smaller telescoping section 44 has the pivotally mounted roller 51 concealed at its inner end, and at its outer end is provided with extension members 52 in which pin 53 is fitted. It also has a notch 59. Pin 53 pivotally connects the display means D to this tip section.

50 The base or larger section 40 does not have a detent 48, but does have the pivotally mounted roller 45 near its outer end, and at its other end has flanges 54, useful for attaching it to rotary member 55, by means of cap screws 56. Rotary member 55 has a projecting pin 57 formed integral with it. Pin 57 passes through hole 30 in anchor plate 28, and mounts the base section 40 for vertical swinging movement about it.

55 Any vertical movement imparted to base section 40 and its attached telescoping members, is regulated by a spring 60 and an air cushion 61, the former tending to counterbalance the weight of the telescoping arm and display means, and the latter serving to check or snub the movement of the arm when it nears the end of its stroke in either direction.

60 The counterbalancing means I have shown comprises the flat coil spring 60 which has a loop 62 at its inner end, and a loop 63 at its outer end. Loop 63 hooks on the under side of pin 64 suitably fastened to base section 40, and exerts on it a lifting effect. Loop 62 hooks in a drum 65 which is loosely mounted on a collar 68 fitted on pin 57. A nut 66 and washer 67, of larger out-

side diameter than collar 68, on the end of pin 57 hold the drum in place and also hold the rotary member 55 in place against circular anchor plate 28. The inner periphery of drum 65 is ratcheted to cooperate with pawl 70, carried on pin 37 mounted in anchor plate 28. By fitting a wrench in holes 71 in the side of drum 65 and rotating it the tension on spring 60 can be increased or decreased to whatever is sufficient to counterbalance the weight of the suspended arm 10 B and display means D. Suitable means such as the wire 69 attached to pawl 70 is provided for lifting it.

Obviously other types of counterbalancing means may be employed which will accomplish 15 an equivalent purpose with that I have used for illustration.

The form of snubber I have shown generally at 61 is of the dash-pot type, although other types may be employed. It comprises a closed 20 cylindrical chamber 72, adapted to contain a fluid. In one end of the cylinder is secured a bolt 73, having a nut 74 threaded on its end and set away from the end of the cylinder. The other end of the cylinder is closed by a cap 75 through 25 which a piston rod 76 projects. A suitable packing 77 and gland nut 78 is provided around rod 76. Piston 80 is secured to the end of rod 76 and has restricted passageways 81 and 82 drilled in 30 its body, with suitable checkvalves 83 set therein. By checking the flow of fluid through the checkvalves in the piston the movement of rod 76 and bolt 73 toward or away from each other can be controlled.

Piston rod 76 is pivoted at 84 to yoke 85, suitably attached to base section 40 by angle bracket 86. Bolt 73 passes freely through a hole in block 87, pivotally mounted on bracket 88, attached by bolts 90 to boss 27 on tubular member 25. In Fig. 6 the parts are shown in the position they 45 occupy when the telescoping arm B is in its lowered position. Notice that nut 74 on bolt 73 is away from block 87 and piston rod 76 is inside chamber 72. In Fig. 2 arm B is in its raised position and nut 74 on bolt 73 is now against 50 block 87 and piston rod 76 has moved piston 80 to the other end of chamber 72. The lost motion provided by having bolt 73 slidably in block 87 is to permit arm B unrestricted movement 55 during the first part of its travel in either direction and to check its movement only as it approaches the up or the down position.

It is desirable that some means of adjustment be provided to regulate the position of the arm B when in lowered position and in raised position. I care for this in the former case by having adjusting bolt 120, with lock nut 121 threaded in boss 122, which bears against tubular member 25. In the raised position the regulation is obtained by nut 74 on bolt 73, or by adjusting 60 bolt 123, with lock nut 124, threaded in boss 125, which bears against tubular member 25.

The display means D comprises the tray 91, formed with side walls 92, and may have partitions (not shown) spaced to receive certain special packages of merchandise. At its corners soft pads 99 prevent it from injuring, denting or scratching anything it may contact. The tray is suitably fastened to bracket 93, which is on the top end of upright 94. Near its lower 70 end it is enlarged at 95 to provide a bearing surface 96 to coact with bearing surface 97 on member 98. Its tip end is threaded to receive nut 100 which holds it loosely in member 98. Part of the collar 95 is cut away (see Fig. 4) 75

and a stop pin 101 is set in bearing surface 97 to limit the extent of rotation of upright 94 and tray 91.

Member 98, besides providing the bearing for upright 94, has depending arms 102 and 103, with weights 104, 105 secured at their lower ends by bolts 106 and 107. Near their upper ends, depending arms 102 and 103 are pivoted to the end of the tip telescoping section 44 by pin 53. The weights thus can establish the tray in a predetermined level position, regardless of the position of telescoping arm B.

On the top side of arm member 44 may be pivoted a pawl 110 with an actuating pin 111 and spring 112. The pawl engages a slot 113 in member 98 and when engaged serves to hold the tray mounting means in a rigid position (see Fig. 1). The pawl may be released when the arm B is completely telescoped (see Fig. 4) and I have shown one mechanism for doing this, which comprises an arm 114 mounted in section 40 and having its end tapered to ride up on the surface of bracket 115 and lift pawl 110 by contacting actuating pin 111. With pawl 40 released and the arm telescoped, the tray 91 will remain level as the arm swings it into the position shown in Fig. 2. In this position the weights 104 and 105 nest in against arm section.

Pin 53 has an extension 108 and handle 109 attached to it to serve in adjusting the position of the arm B.

Operation

Assuming the device is in the position of Fig. 2, the station attendant grasps handle 109 and pulls the tray 91 into the position shown in Fig. 9. This may bring the tray into position within reach of the customer seated in the vehicle. Any additional movement of the tray required to bring it within reach of the customer is effected by further pulling on handle 109 which results in the sections 40, 41, 42, 43 and 44 sliding within each other. The maximum reach, or unfolding possible is shown in Fig. 1.

By means of the spring mounted detents or pawls 48, and notches 50 the intermediate sections 41, 42 and 43 and the tip section 44 are interlocked and the first movement, on unfolding, results in section 41 moving out of section 40. When its detent 48 passes beyond the end of section 40 it releases the lock between section 41 and 42, so that section 42 moves out of section 41. This is repeated with the others so that the tip section 44 is the last to move. The reason for controlling the unfolding is to have as little overhang as possible between the section that is moving and the tray. In other words, if the telescoping arm unfolded first the tip section and then each succeeding section, the friction, strain on rollers, etc. would be unnecessarily multiplied by the time section 42 was moving out of 41, and 41 out of 40.

When the display device is to be returned to the position shown in Fig. 2, the attendant grasps handle 109, or takes hold of the tray itself and pushes in a horizontal direction until he has telescoped the extended sections. This causes the arm 114 to lift pawl 110 and member 98 is

free to rotate about pin 53. The attendant lifts slightly on handle 109 and spring 60 cooperates to lift the tray into the raised position.

While I have shown the device as rigidly mounted on an "island", it is not limited to this type of installation. For instance, in Fig. 9 I have shown diagrammatically, two optional mountings. The bracket 120 is adapted to a wall mounting. The bracket 121 (in broken lines) is adapted for a ceiling mounting. Other forms of mountings would be to attach the flange 22 (Fig. 1) to a truck moving on tracks on the "island" so as to avoid the gasoline pumps and give a greater reach in a forward and backward direction parallel with the island; or pivotally mounted off center with respect to the base by means of pin 25 in the tubular portion of link 33, which is in turn pivotally mounted at its other end on base 21 by means of pin 32. The latter construction is particularly advantageous where gasoline pumps are arranged on the "island" and the display tray when in service must lie parallel to the island, but avoid the pumps.

Consequently, it is to be understood that the forms of my invention, herewith shown and described, are to be taken as preferred examples of the same, and that various changes in the shape, size and arrangement of parts may be resorted to, without departing from the spirit of my invention, or the scope of the subjoined claims.

Having thus described my invention, I claim:

1. In a display apparatus the combination of a base, an arm hinged to said base, said arm comprising a plurality of short sections which can be extended, means for controlling the order of extension of said sections whereby the unextended section nearest the base is the first to move into extended position, and display means pivotally attached to said arm.

2. In a display apparatus the combination of a base, an arm hinged to said base, said arm comprising a plurality of sections which can be extended, display means pivotally attached to said arm, and means for limiting the pivotal movement of said display means when said sections are extended and for allowing free pivotal movement when they are telescoped whereby said arm may move vertically without disturbing the level position of said display means.

3. In a display apparatus adapted for universal movement about a fixed base, the combination of a base, an anchor member pivotally mounted in said base, an arm pivotally connected to said anchor member, counterbalancing means for lifting said arm, means for controlling the rate of movement of said arm about its pivot, and display means pivotally attached at the end of said arm.

4. In a display apparatus the combination of a base, an arm hinged to said base, said arm comprising a plurality of short sections telescoped within each other and adapted to be extended, latch means controlling the order of extension of said sections whereby the order of extension is regulated to allow relative extensible movement successively beginning with the section nearest the base.

CLINTON L. WALKER.
